UNITED STATES PATENT OFFICE.

JAMES TORSTEN SANDBERG, OF GOTTERBORG, SWEDEN.

BELT-PULLEY AND SIMILAR DEVICE.

1,382,321.

Specification of Letters Patent. Patented June 21, 1921.

Application filed April 3, 1920. Serial No. 370,926.

To all whom it may concern:

Be it known that I, JAMES TORSTEN SANDBERG, a subject of the King of Sweden, residing at Gottenborg, in the county of Gottenborg and Bohus and Kingdom of Sweden, have invented new and useful Improvements in Belt-Pulleys and Similar Devices, of which the following is a specification.

This invention refers to belt pulleys and similar devices, which consist of a body of cast iron or the like, undivided or subdivided in two or more parts and provided with a sheet iron rim, which is in suitable manner attached to the body.

15 The principal object of this invention is to provide improved means for attaching the sheet iron rim to the annular web portion of the body of the pulley.

Other objects of the invention will be 20 clearly understood by the following specification, reference being made to the accompanying drawing, illustrating some embodiments of the invention.

In the drawing Figure 1 shows a side view 25 of a belt pulley and Fig. 2 an axial section of the same. Figs. 3, 4, 5 and 6 show in axial sections a portion of the rim, attached to the web portion according to various embodiments of the invention. Fig. 7 shows a portion 30 of the rim viewed from the inner side and showing one arm of the pulley in section.

In the drawing the invention is illustrated 35 as applied to a pulley subdivided in two parts for facilitating the application of the pulley in a shaft, but I do not limit myself to such a special form of this invention.

In the drawing 1 denotes the one half of 40 the divided body of the pulley and 2 the arms, connected with the hub portion 3 and with the annular web portion 5. 6 denotes the sheet iron rim, according to the embodiment, shown in the drawing, divided in two halves, which are joined together by means 45 of angle bent lugs 8 provided on the inner side at the ends of the rim 6. The halves of the pulley can as known be clamped to a shaft by means of screwbolts 13.

The web portion 5, of cast iron or similar 50 material, is provided with plate iron brackets of various shapes 10, projecting from the web 5 in axial direction and cast into the web 5.

The projecting ends of the brackets 10 are attached to the rim 6 by means of rivets 55 14 or bolts 15 or by electrical or autogenous soldering or welding. In Fig. 6 washers 16, 17 are provided between the rim 6 and the brackets 10.

The brackets 10 may be bent to follow the 60 inside shape of the rim 6, so that, if the rim be straight lined in axial direction as illustrated in Figs. 2, 4, 5 and 6, the brackets are formed with straight lined projecting ends, or if the rim be convex, as shown in 65 Fig. 3 with curved ends sloping down the inside of the rim 6. The inner ends 11 of the brackets 10, which are cast into the body portion 5 may be angle bent in relation to the projecting portions of the brackets, so 70 that they are safely secured in the body 5. Moreover it may be advantageous to cast the brackets in the web portion 5 at a certain distance apart from the outer periphery of the said portion and to make a bend outward to the joint with the rim 6 such as 75 clearly illustrated in the Figs. 2-5, thereby increasing the stiffening effect upon the rim. Somewhat the same result is obtained by the device shown in Fig. 6 by means of the 80 washers 16, 17.

I do not limit myself to the shape of the brackets 10 as described and illustrated in the drawing but I want to vary this detail 85 without interfering with the scope of my invention. For instance the two brackets 10 projecting on each side of the web portion can be substituted by a single piece forming the double end projecting bracket.

What I claim is:

1. In a belt pulley a cast iron web portion, a sheet iron rim encircling said web portion, brackets joining said rim to said web portion and cast in the web by means of angle bent ends.

2. In a belt pulley a cast iron web portion, a sheet iron rim encircling said web portion, brackets joining said rim to said web portion and having angle bent ends cast in the web at some distance from the periphery of said web portion and bent outwardly toward the inner-surface of the rim forming stiffening supports for the rim.

3. In a belt pulley a cast iron web portion, a sheet iron rim encircling said web portion, brackets joining said rim to said

web portion and having angle bent ends cast in the web, washers arranged between the brackets and the inner surface of the rim.

4. In a belt pulley, a cast iron web portion, a sheet iron rim encircling said web portion, sheet metal brackets joining said rim to said web portion and having inner

ends cast in the web, and means securing the outer ends of said brackets to the inner surface of said rim.

In testimony whereof I have affixed my signature.

JAMES TORSTEN SANDBERG.
